WASHING APPARATUS

Nils Pablo Roxendorff, Rasunda, Sweden, assignor, by mesne assignments, to Aktiebolaget Lavator, Stockholm, Sweden

Application July 23, 1930, Serial No. 470,073, and in Germany June 6, 1930

2 Claims. (Cl. 68—30)

This invention relates to washing-apparatus of the thermosiphon type, i. e. to washing-apparatus in which the washing liquid is exclusively circulated by the effect of the heat to flow through the clothes and other articles to be washed but no mechanical or moving parts are used for moving the washing liquor or the clothes or for rubbing the latter. It was, however, heretofore difficult or rather impossible to attain a good washing in such apparatus, because the circulation of the washing liquid could not be made sufficiently strong and efficient. Because no mechanical rubbing of the articles to be washed is made in such apparatus of the thermosiphon type very high requirements must be made upon the efficiency of the circulation.

The chief object of this invention is to provide for a washing apparatus of the type described having a very intensive circulation of the washing liquid and, thus, giving a very good washing result. For this purpose, the apparatus is divided into an upper and a lower chamber by means of a partition wall having at least in its central portion an upward cambered or dished shape, for instance, the shape of a truncated cone, and, furthermore, a riser extends substantially vertically from the central portion of said partition wall and the bottom of the apparatus, below which a separate heating device is, as usual, provided for, is correspondingly cambered in order to form, between said bottom and said partition wall, a lower chamber being at least in its centre cambered upwards and communicating with the upper chamber, enclosing the articles to be washed, via one or more sockets or down pipes provided close by the outer periphery of the apparatus.

The steam bubbles generated in this lower chamber by the heating have a tendency of rising to the highest point of the cambered or curved portion and of rising further in the rising tube causing the washing liquid to rise and then to fall down upon the articles to be washed and to penetrate them, whereupon said liquid flows back to the lower chamber through the socket or sockets. Because of the dished shape of the bottom of the apparatus the heating surface is increased and at the same time the heating is concentrated in the centre thereof. The curved or cambered shape of the partition wall forces the steam bubbles to move towards the centre while simultaneously rising and consequently said bubbles cannot impede the washing liquid flowing down through the sockets or down pipes in its movement downwards. As a result of those co-operating features the circulation is very intensive

and much superior to that of all washing apparatus of this type heretofore known.

One embodiment of the invention is shown in the annexed drawing, in which Fig. 1 is a vertical central section through a washing apparatus according to the invention, part of the apparatus being, however, shown in elevation while Fig. 2 is a horizontal section on the line II—II in Fig. 1.

Referring now to the drawing 1 is a cylindrical washing vessel having a bottom 2 rigidly secured thereto. This bottom has in its central portion the shape of a cone, whose top is turned upwards. Above this bottom a stationary partition wall is attached to the cylinder 1 said wall having a shape similar to that of the bottom and comprising a plane portion 4 and a conical portion 5. Close by its periphery said partition wall is provided with two sockets or short down pipes 6 diametrically opposite to each other, through which the lower chamber between the partition wall 4, 5 and the bottom 2, 3 communicates with the upper portion of the cylinder 1. The down pipes 6 extend so far downwards that they end close above the bottom 2. The number of said down pipes is arbitrary.

On the upper side of the partition wall 4 an annular support or rail 7 is fixed on which a detachable inner bottom 8 is resting provided with a number of holes 9 and two vertical standards 10 having handles 11 at their upper ends. By means of said handles the inner bottom may be shaken and also lifted out of the vessel 1. In the centre of the inner bottom there is an opening through which the upper portion of the cone 5 projects upwards said cone 5 being truncated and joined to a substantially vertical rising tube 12. Close by its upper end said rising tube has an annular supporting collar or flange 13 round it said collar serving to support a cylindrical supporting tube or socket 14 secured to the bottom of a low distribution chamber 15. As seen in Fig. 1, the tube 14 projects somewhat above the bottom of the chamber 15 and thus a throttled passage is formed between the upper edge of said socket and the cover of the chamber 15. The tube 14 serves to support the whole chamber 15 which fills up almost the whole cross-section of the vessel 1 and may, together with the tube 14 be lifted out of the vessel 1. In the bottom of the distribution chamber 15 a number of openings 16 are provided for and to the upper side of said chamber straps or handles 17 are secured to facilitate the removal of the chamber from the vessel.

On the vessel 1 a second minor vessel or con-

tainer 18 is placed forming a cover for said vessel 1. This container 18 serves as a hot water preparer and is heated by the steam rising from the vessel 1 and coming in contact with the bottom 5 of said container. The hot water thus prepared is utilized as rinsings for the clothes or for other purposes. At a short distance below the container 18 the inner wall is perforated at 19 in order to prevent any pressure above atmospheric 10 to be generated in the vessel 1. The presence of such a pressure above atmospheric would otherwise interfere with the good operation of the apparatus. At the bottom of the apparatus a cock 20 is provided for by use of which the 15 whole apparatus may be emptied, if desired.

Below the bottom 2 of the apparatus a heating device of conventional design, for instance a gas burner 21 is provided for, which, however, does not belong to the apparatus proper nor is integral 20 with the boiler.

The apparatus described acts as follows:

In order to render it possible to put the articles to be washed into the apparatus the container 18 and the removable distribution chamber 25 15 are lifted off, whereupon the clothes etc. are placed on the inner bottom 8. If it is desired to soak the clothes prior to the washing proper the vessel 1 is filled with water and the clothes may also be agitated in this water by use 30 of the handles 11 by which the inner bottom together with the clothes thereon may be lifted and rotated in the soak water, if desired. Then this water is let out through the cock 20. It is, however, understood that the soakage may be 35 made in a separate vessel and also that the soakage may be dispensed with.

Then the vessel 1 is filled to a suitable level with a washing liquid, for instance, soap-suds, the chamber 15 and the container 18 are restored to 40 their places and the heating device 21 is started. As a result of the curved or dished shape of the bottom 2, 3 the heating surface is much larger than that of a plane bottom of the common type and, moreover, the flames will be concentrated in 45 the conical portion 3 thus causing the most intensive generation of steam and heating of the washing liquid to take place there. The steam bubbles generated in the lower chamber between the fixed partition wall 4, 5 and the bottom 3 rise, as 50 indicated by arrows in the drawing, between the conical structures 5 and 3 and further through the riser 12 and move the washing liquid in the same direction causing said liquid to rise into the distributive chamber 15. The tube 14 projecting 55 upwards into said chamber forms a throttled passage at the cover of said chamber and thus serves to throw the liquid far outwards substantially radially in all directions in order to distribute it more uniformly over the perforated bottom of 60 said chamber than would otherwise be the case. In some cases the distribution may be made even more uniform by the reduction of the holes 16 in size from the periphery towards the centre. The 65 washing liquid then flows downwards through said holes 16 and flows through the clothes etc. placed on the inner bottom 8 and thereafter is returned to the lower chamber through the openings 9 and the down pipes 6. The circulation is in Fig. 1 of the drawing indicated by arrows. Because 70 the steam bubbles gather immediately below the partition wall 4 and follow this wall on to the cambered portion 5, along which they rise, practically no steam can rise through the down pipe 6 and consequently substantially all the steam generated aids in bringing about the circula-

tion (the thermo-siphon effect). As a result of this and of the large heating surface and the shape of the parts used the circulation is much more strong and efficient than that of the washing apparatus known heretofore and the washing is consequently much better and more effective.

The quantity of the washing liquid is chosen in such manner that during the circulation the liquid surface or level in the upper portion of the vessel 1 is below the inner bottom 8 and, therefore, the circulation through the clothes etc. on the inner bottom 8 is not impeded by the liquid gathering at the bottom of the vessel 1. When the circulation has lasted for a sufficiently large time, the heating is cut off and the washing liquid is let out through the cock 20. After the removal of the container 18 and, if desired, also the distributive chamber 15 a rinsing liquid such as hot water from the container 18 may be filled into the vessel 1 and the clothes etc. on the inner bottom 8

80

may be moved to and fro in the rinsing liquid by use of the handles 11 until a thorough rinsing has been made. This may be repeated several times. After each rinsing the liquid is drawn off through the cock 20 and finally the inner bottom 8 together with clothes thereon is lifted out by means of the handles 11, whereupon a new charge of clothes may be placed in the apparatus for washing.

85

Below the bottom 2 of the apparatus a heating device of conventional design, for instance a gas burner 21 is provided for, which, however, does not belong to the apparatus proper nor is integral 20 with the boiler.

90

The apparatus described acts as follows:

In order to render it possible to put the articles to be washed into the apparatus the container 18 and the removable distribution chamber 15 are lifted off, whereupon the clothes etc. are placed on the inner bottom 8. If it is desired to soak the clothes prior to the washing proper the vessel 1 is filled with water and the clothes may also be agitated in this water by use 45 of the handles 11 by which the inner bottom together with the clothes thereon may be lifted and rotated in the soak water, if desired. Then this water is let out through the cock 20. It is, however, understood that the soakage may be made in a separate vessel and also that the soakage may be dispensed with.

95

Then the vessel 1 is filled to a suitable level with a washing liquid, for instance, soap-suds, the chamber 15 and the container 18 are restored to 50 their places and the heating device 21 is started. As a result of the curved or dished shape of the bottom 2, 3 the heating surface is much larger than that of a plane bottom of the common type and, moreover, the flames will be concentrated in the conical portion 3 thus causing the most intensive generation of steam and heating of the washing liquid to take place there. The steam bubbles generated in the lower chamber between the fixed partition wall 4, 5 and the bottom 3 rise, as 55 indicated by arrows in the drawing, between the conical structures 5 and 3 and further through the riser 12 and move the washing liquid in the same direction causing said liquid to rise into the distributive chamber 15. The tube 14 projecting upwards into said chamber forms a throttled passage at the cover of said chamber and thus serves to throw the liquid far outwards substantially radially in all directions in order to distribute it more uniformly over the perforated bottom of said chamber than would otherwise be the case. In some cases the distribution may be made even more uniform by the reduction of the holes 16 in size from the periphery towards the centre. The washing liquid then flows downwards through said holes 16 and flows through the clothes etc. placed on the inner bottom 8 and thereafter is returned to the lower chamber through the openings 9 and the down pipes 6. The circulation is in Fig. 1 of the drawing indicated by arrows. Because the steam bubbles gather immediately below the partition wall 4 and follow this wall on to the cambered portion 5, along which they rise, practically no steam can rise through the down pipe 6 and consequently substantially all the steam generated aids in bringing about the circulation.

100

Below the bottom 2 of the apparatus a heating device of conventional design, for instance a gas burner 21 is provided for, which, however, does not belong to the apparatus proper nor is integral 20 with the boiler.

105

The apparatus described acts as follows:

In order to render it possible to put the articles to be washed into the apparatus the container 18 and the removable distribution chamber 15 are lifted off, whereupon the clothes etc. are placed on the inner bottom 8. If it is desired to soak the clothes prior to the washing proper the vessel 1 is filled with water and the clothes may also be agitated in this water by use 45 of the handles 11 by which the inner bottom together with the clothes thereon may be lifted and rotated in the soak water, if desired. Then this water is let out through the cock 20. It is, however, understood that the soakage may be made in a separate vessel and also that the soakage may be dispensed with.

110

Then the vessel 1 is filled to a suitable level with a washing liquid, for instance, soap-suds, the chamber 15 and the container 18 are restored to 50 their places and the heating device 21 is started. As a result of the curved or dished shape of the bottom 2, 3 the heating surface is much larger than that of a plane bottom of the common type and, moreover, the flames will be concentrated in the conical portion 3 thus causing the most intensive generation of steam and heating of the washing liquid to take place there. The steam bubbles generated in the lower chamber between the fixed partition wall 4, 5 and the bottom 3 rise, as 55 indicated by arrows in the drawing, between the conical structures 5 and 3 and further through the riser 12 and move the washing liquid in the same direction causing said liquid to rise into the distributive chamber 15. The tube 14 projecting upwards into said chamber forms a throttled passage at the cover of said chamber and thus serves to throw the liquid far outwards substantially radially in all directions in order to distribute it more uniformly over the perforated bottom of said chamber than would otherwise be the case. In some cases the distribution may be made even more uniform by the reduction of the holes 16 in size from the periphery towards the centre. The washing liquid then flows downwards through said holes 16 and flows through the clothes etc. placed on the inner bottom 8 and thereafter is returned to the lower chamber through the openings 9 and the down pipes 6. The circulation is in Fig. 1 of the drawing indicated by arrows. Because the steam bubbles gather immediately below the partition wall 4 and follow this wall on to the cambered portion 5, along which they rise, practically no steam can rise through the down pipe 6 and consequently substantially all the steam generated aids in bringing about the circulation.

115

Below the bottom 2 of the apparatus a heating device of conventional design, for instance a gas burner 21 is provided for, which, however, does not belong to the apparatus proper nor is integral 20 with the boiler.

120

The apparatus described acts as follows:

In order to render it possible to put the articles to be washed into the apparatus the container 18 and the removable distribution chamber 15 are lifted off, whereupon the clothes etc. are placed on the inner bottom 8. If it is desired to soak the clothes prior to the washing proper the vessel 1 is filled with water and the clothes may also be agitated in this water by use 45 of the handles 11 by which the inner bottom together with the clothes thereon may be lifted and rotated in the soak water, if desired. Then this water is let out through the cock 20. It is, however, understood that the soakage may be made in a separate vessel and also that the soakage may be dispensed with.

125

Then the vessel 1 is filled to a suitable level with a washing liquid, for instance, soap-suds, the chamber 15 and the container 18 are restored to 50 their places and the heating device 21 is started. As a result of the curved or dished shape of the bottom 2, 3 the heating surface is much larger than that of a plane bottom of the common type and, moreover, the flames will be concentrated in the conical portion 3 thus causing the most intensive generation of steam and heating of the washing liquid to take place there. The steam bubbles generated in the lower chamber between the fixed partition wall 4, 5 and the bottom 3 rise, as 55 indicated by arrows in the drawing, between the conical structures 5 and 3 and further through the riser 12 and move the washing liquid in the same direction causing said liquid to rise into the distributive chamber 15. The tube 14 projecting upwards into said chamber forms a throttled passage at the cover of said chamber and thus serves to throw the liquid far outwards substantially radially in all directions in order to distribute it more uniformly over the perforated bottom of said chamber than would otherwise be the case. In some cases the distribution may be made even more uniform by the reduction of the holes 16 in size from the periphery towards the centre. The washing liquid then flows downwards through said holes 16 and flows through the clothes etc. placed on the inner bottom 8 and thereafter is returned to the lower chamber through the openings 9 and the down pipes 6. The circulation is in Fig. 1 of the drawing indicated by arrows. Because the steam bubbles gather immediately below the partition wall 4 and follow this wall on to the cambered portion 5, along which they rise, practically no steam can rise through the down pipe 6 and consequently substantially all the steam generated aids in bringing about the circulation.

130

Below the bottom 2 of the apparatus a heating device of conventional design, for instance a gas burner 21 is provided for, which, however, does not belong to the apparatus proper nor is integral 20 with the boiler.

135

The apparatus described acts as follows:

In order to render it possible to put the articles to be washed into the apparatus the container 18 and the removable distribution chamber 15 are lifted off, whereupon the clothes etc. are placed on the inner bottom 8. If it is desired to soak the clothes prior to the washing proper the vessel 1 is filled with water and the clothes may also be agitated in this water by use 45 of the handles 11 by which the inner bottom together with the clothes thereon may be lifted and rotated in the soak water, if desired. Then this water is let out through the cock 20. It is, however, understood that the soakage may be made in a separate vessel and also that the soakage may be dispensed with.

140

Then the vessel 1 is filled to a suitable level with a washing liquid, for instance, soap-suds, the chamber 15 and the container 18 are restored to 50 their places and the heating device 21 is started. As a result of the curved or dished shape of the bottom 2, 3 the heating surface is much larger than that of a plane bottom of the common type and, moreover, the flames will be concentrated in the conical portion 3 thus causing the most intensive generation of steam and heating of the washing liquid to take place there. The steam bubbles generated in the lower chamber between the fixed partition wall 4, 5 and the bottom 3 rise, as 55 indicated by arrows in the drawing, between the conical structures 5 and 3 and further through the riser 12 and move the washing liquid in the same direction causing said liquid to rise into the distributive chamber 15. The tube 14 projecting upwards into said chamber forms a throttled passage at the cover of said chamber and thus serves to throw the liquid far outwards substantially radially in all directions in order to distribute it more uniformly over the perforated bottom of said chamber than would otherwise be the case.
